UNITED STATES PATENT OFFICE.

FRANK RUSSELL ALLEY, OF SEATTLE, WASHINGTON.

COMMUTATOR-SLOTTER.

1,083,175.

Specification of Letters Patent.

Patented Dec. 30, 1913.

Application filed May 28, 1913. Serial No. 770,349.

To all whom it may concern:

Be it known that I, FRANK RUSSELL ALLEY, a citizen of the United States, and a resident of Seattle, in the county of King and State of Washington, have invented a new and Improved Commutator-Slotter, of which the following is a full, clear, and exact description.

This invention relates to a hand tool for slotting commutators, and it has for its general object to provide an improved tool of comparatively simple and inexpensive construction whereby the slots between the commutator bars of a dynamo electric machine can be quickly and accurately made and with uniformly good results.

Another object of the invention is the provision of a tool embodying a guide and a cutter so related with respect to each other that the cutter can operate between two commutator bars while the guide is engaged in a slot already formed between two other commutator bars, said guide serving to enable a slot to be started, and thereafter the tool is tilted to throw the guide out of its slot for enabling the cutter to perform its work of cutting a slot by the reciprocation of the tool, and the guide and cutter can be thrown into or out of parallelism as the condition of the commutator may require.

Another object of the invention is the provision of novel adjusting means on the body of the tool whereby the guide and cutter can be spaced apart any desired distance for enabling slots to be cut in the commutator at widely spaced points where only a few slots can be cut at any one time while the machine is idle, an additional group of slots being cut at another time, and so on until the commutator is completed. In this manner the commutator may be kept absolutely true, which would not be the case if a group of slots were cut at one side of the commutator at one time and another group at another time, and so on.

With these objects in view, and others as will appear as the description proceeds, the invention comprises various novel features of construction and arrangement of parts which will be more fully described herein-after and set forth with particularity in the claims appended hereto.

In the accompanying drawings, which illustrate one embodiment of the invention, and wherein similar reference characters are employed to designate corresponding parts

throughout the several views, Figure 1 is a plan view of the tool with a portion broken away; Fig. 2 is a side view with a portion in section on the line 2—2 of Fig. 1; Fig. 3 is a transverse section on the line 3—3 of Fig. 1; and Fig. 4 is a side view of the guide detached.

Referring to the drawing, A designates the body of the tool, which body is an aluminum or other metal casting that is formed with transversely-disposed parallel slots 1 and 2, in which are slidably mounted posts 3 and 4, respectively, said posts extending below the bottom of the body A and each formed with a dove-tailed slot to form jaws 5 for receiving a cutter which is preferably, although not necessarily, a triangular file 6 that is clamped in place by set-screws 7 in the jaws. This cutter extends parallel with the longitudinal edges of the body and is parallel with a guide 8 which is in the form of a plate or bar having at its lower edge a lining groove-engaging runners 9. This plate has four openings or slots 10 for receiving screws 11 which are threaded in openings 12 in the side of the body A. By loosening these screws the guide 8 can be adjusted up or down so as to adapt the tool for commutators of different curvatures.

The cutter 6 and guide 8 are relatively adjustable toward and from each other so that the tool can span a plurality of commutator bars. For this adjustment the posts 3 and 4 are slidable in their respective guideways or grooves 1 and 2, each post having an adjusting screw 13 swiveled at 14 in the wall or portion of the body adjacent the guide 8, the opposite end of the screw being formed with a milled head or knob 15 whereby the screw can be readily turned. The screw is threaded in an opening 16 in the cutter-carrying post and after the posts are properly adjusted accidental change in the adjustment is prevented by set-screws 17 in each post binding on the screw 13, there being a spring washer 18 inserted between the heads of the screws 17 and the plate 19 which slidably engages the top surface of the body A.

In using the tool the mica between two bars of the commutator is cut away by the file 6 without making use of the guide 8. In cutting the second groove, however, the cut is guided by the guide 8 being entered in the first groove, whereby the tool is reciprocated back and forth in a straight line. After the groove has been well started the

- tool is tilted slightly so as to disengage the guide from the first slot while the second slot is completed. The third slot is begun by placing the tool in such a position that 5 the guide will engage the second slot and the operation just described is repeated. In this manner the operation is continued until all the slots between the commutator bars are made.
- 10 With a tool of this character it will be found that a slot can be made by hand in less than a minute and better results obtained with less liability of injuring the surface of the commutator, than with other 15 methods, such as hand filing, scraping or sawing, which take from four to seven minutes to make a slot, and then there is danger of injuring the surface of the commutator.
- 20 It will be noted that the ends of the file or cutter can be independently adjusted to throw it out of parallelism with the guide, as will be necessary when the bearing end of the commutator is smaller than the armature end, which condition of the commutator has been brought about by truing the 25 commutator from time to time with sandpaper or with a grinding machine, as is sometimes done.
- 30 From the foregoing description taken in connection with the accompanying drawings, the advantages of the method of operation and of the device shown will be readily understood by those skilled in the art to 35 which the invention appertains, and while I have described the device which I now con-

sider to be the best embodiment thereof, I desire to have it understood that the device shown is merely illustrative, and that such changes may be made when desired as are 40 within the scope of the appended claims.

Having thus described my invention, I claim as new and desire to secure by Letters Patent:

1. A commutator slotting tool comprising 45 a body having transversely-extending guideways disposed parallel and spaced apart, a single rotating element in each guideway, a member engaged with each element and moved longitudinally thereof by rotation of 50 the elements, a cutter mounted on the members and disposed below the same and below the body, and a guide adjustably mounted on the body and extending substantially parallel with the cutter.

2. A commutator slotter comprising a rectangular body having at one end parallel transversely-extending guideways, a screw rotatable in each guideway, a member movable in each guideway and connected with 60 the screw, a cutter mounted in each member and having its ends extending beyond the ends of the body, and a guide on one side of the cutter and adjustable vertically to vary 65 the relation of the guide to the cutter.

In testimony whereof I have signed my name to this specification in the presence of two subscribing witnesses.

FRANK RUSSELL ALLEY.
